TELEGRAPH SYSTEM

Ernest Harris Jolley and John Arthur Stanley
Martin, Harrow, England, assignors to Auto-
matic Electric Company Limited, Liverpool,
England, a British company

Application January 26, 1933, Serial No. 653,736
In Great Britain February 3, 1932

7 Claims. (Cl. 178—53.1)

The present invention relates to electric telegraph and like systems and is more particularly concerned with systems in which signals are represented by elements of different wave forms, for instance, systems in which the elements are of different lengths composed of varying numbers of units. The invention moreover is more particularly concerned with systems of the so-called start-stop type in which the necessity for accurate synchronism between the transmitting and receiving equipment is avoided by arranging that each signal is preceded by a start impulse and followed by a stop impulse so that as the error is non-cumulative accurate correspondence between the speeds of the equipment at the transmitting and receiving end is not necessary.

In long distance transmission, particularly over underground cables, the different elements tend to become distorted with respect to time on account of the electrical characteristics of the line and/or of interference from outside sources. The object of the present invention is to provide simple and effective means whereby such distorted signals may be regenerated and restored to their original form, the regenerated signals being then transmitted over further line sections or being caused to operate automatic type printing or other recording apparatus in circumstances in which the distortion in the received signals before regeneration is too great to enable the type printing or other mechanism to be satisfactorily operated.

According to one feature of the invention in a telegraph system of the start-stop type regeneration of signals is effected by arranging that a predetermined small portion of each signal unit operates a transmitter from which a re-transmitting relay is controlled in such a manner that it only alters the position of its tongue in response to a reversal of current in the control circuit.

According to another feature of the invention the incoming signals operate an electromagnet which on energization releases a latch to permit a segmented disc to make one revolution and also operates a transmitter from which a circuit is completed over the conducting segments of the disc for operating a re-transmitting relay.

The invention will be better understood from the following description of two methods of carrying it into effect which should be taken in conjunction with the accompanying drawing comprising Figs. 1 and 2. The invention is shown applied to a start-stop telegraph system arranged in the usual manner so that each signal comprises seven units, one for start, one for stop and

five for determining the actual character of the signal. It will be assumed for a matter of convenience that the invention is applied to what are known as teleprinters in which the operation of a keyboard similar to that of a typewriter produces a typed message at both the sending and receiving ends.

Referring now to Fig. 1, signal currents incoming over leads 1 and 2 are fed to the polarized receiving relay 3 which on energizing when the current over the line is reversed produces operation of the tongue 4. This thereupon completes an operating circuit for a polarized electro-magnet 5 which is adapted at the end of its stroke to control by means of the member 6 a delayed action transmitter the sending contact of which is represented by 7. The regenerating apparatus includes a segmented disc which is preferably in two parts 12 and 13 which are relatively adjustable and this disc is connected by means of a clutch mechanism with a shaft driven from the motor 8 by means of suitable gearing 9 at a speed slightly in excess of that of the teleprinter transmitter shaft, accurate speed control being effected by a governor 10 in known manner. The disc 12, 13 which comprises seven conducting segments so spaced that when the disc revolves the time intervals at which successive conducting segments are wiped corresponds to the time length of the units comprising the signal is normally prevented from turning, but on the operation of the arm 11 by the energization of magnet 5 the latch which normally holds the disc is released and it is allowed to make one revolution by means of the clutch mechanism. The two portions of the disc are engaged respectively by the brushes 14 and 15 which are supported on an arm 16 movable to permit the most suitable portion of the signal to be selected. The brush 14 is connected to the sending contact 7 of the transmitter while the brush 15 extends by way of resistance 18 and condenser 19 to the primary of the transformer 17. The secondary of this transformer is connected to the polarized transmitting relay 20 the tongue 21 of which serves to repeat the signals over the outgoing line comprising leads 22 and 23. As has already been mentioned the discs 12 and 13 are relatively movable and the adjustment will normally be such that only a comparatively small portion of the conducting segments will overlap. This will mean that the circuit from brush 14 to brush 15 is only completed for a very small portion of the time represented by a signal unit. This time must, however, be greater than

the transmitting time of the transmitting relay 20 or at any rate sufficiently great for the tongue 21 to be moved reliably to the alternate contact.

When the apparatus is in operation the motor 8 will be running continuously and may be employed to drive other regenerative repeaters. On receipt of the start impulse at the beginning of a signal, the tongue 4 of the relay 3 is thrown over to its alternate contact and an operating circuit 10 is completed for magnet 5 which thereupon releases the latch so as to permit the shaft carrying the correcting disc 12, 13 to make one revolution and at the same time operates the transmitter contact 7. It is arranged that a certain delay 15 takes place in the operation of contact 7 in order to permit the discs to attain the requisite speed before the brushes become effective. It will now be seen that for a short portion of each signal unit depending on the relative adjustment of the 20 discs, a circuit will be completed over brushes 14 and 15. It will be appreciated, however, that if the circuit from brush 15 extended directly to relay 20 an impulse would be transmitted to the relay each time the brushes passed over a conducting segment and this would cause chattering 25 of the relay which is clearly objectionable. What is required is that each time a reversal of current takes place in the incoming line circuit the tongue of relay 20 should be positively reversed and that 30 no further current should then flow until operation in the other direction is to take place. It is for fulfilling this requirement that the special arrangement shown in Fig. 1 is employed. As 35 previously mentioned, the circuit for the primary of transformer 17 includes resistance 18 and condenser 19 and the values of these components are so chosen that they form an oscillatory circuit with considerable damping and of such period that the first pulse occupies substantially the 40 same time as that during which the signal is repeated over brushes 14 and 15. This means that condenser 19 will be substantially fully charged while the circuit is completed in respect of one signal unit but that there is no time for current to flow in the reverse direction. Moreover, the current flow is zero at the instant that 45 the brushes are leaving the conducting segment and this is of practical importance since normal spark quench devices cannot be employed. If the succeeding signal unit is of the same sign no further change takes place since condenser 19 is 50 fully charged. When the current in the incoming line is reversed, however, transmitter contact 7 is operated and when the connection between 55 brushes 14 and 15 is established a flow of current takes place to charge condenser 19 in the opposite direction. This current flowing through the primary of transformer 17 induces a current in the 60 secondary which effects the operation of relay 20 and thus retransmits the signals over the outgoing line. It may be mentioned that with a disc speed and segment length such that brushes 14 and 15 are connected together for 3 milliseconds a value for resistance 18 of 2000 ohms and 65 a value for condenser 19 of 0.5 microfarads have given good results. These values are of course to some extent dependent on the value of the inductance of the primary of the transformer 7 which is conveniently an ordinary telephone line transformer.

In certain circumstances it may be necessary to bring the disc to rest in such a position that the brushes remain in contact with the last conducting segment. In order that when the trans-

mitter changes over on receipt of the start signal for the next letter the re-transmitting relay shall not be immediately operated, it may be arranged that the connection of the positive pole of the battery associated with the transmitter shall only be connected when the disc is in motion and disconnected when the disc is at rest. 5

Consideration will now be given to the alternative arrangement shown in Fig. 2. In this case the retransmitting relay instead of being strongly 10 polarized is provided with a bias winding and use is made of a thermionic valve for ensuring that impulses for operating the relay shall only be sent when the signal currents change sign. In this case owing to the almost complete lack of 15 inertia of the valve, the portion of the signal units used for regenerating may be even smaller and thus a greater degree of distortion can be satisfactorily corrected.

The two relatively movable halves of the segmented disc represented in Fig. 2 by 33 and 34 are wiped over by the brushes 35 and 36 and are driven in the same manner as in the arrangement of Fig. 1, control by the incoming signals being also similar. The operation of the delayed transmitter contact 31, however, in this case connects up one or other pole of the battery 32 to brush 36. The valve 39 is provided with the usual grid bias battery 40, filament battery 41 and anode battery 42 and the relay 43 provided with contact 44 has a bias winding which with the circuit shown receives current continuously from battery 42 over resistance 45. The values of the grid bias applied from battery 40 by way of the grid leak 38 is such that normally practically no 35 current flows in the anode circuit and tongue 44 is held in the position shown by current flow through the bias winding. When the transmitter contact 31 is operated, however, the positive pole of battery 32 is connected up for a short interval 40 over brushes 35 and 36 and potential thus applied to the grid of the valve permits anode current to flow and also charges up condenser 37. The current flow through the operating winding of 45 relay 43 now overcomes the effect of the bias winding and causes tongue 44 to engage its alternate contact to retransmit the signal over the outgoing line. The condenser 37 is necessary to maintain the grid potential during the portion 50 of the signal unit when battery 32 is not connected up and the grid leak 38 is of such value that no appreciable discharge of condenser 37 will take place while the brush is passing between two of the conducting segments but the condenser will not hold its charge for an extended 55 period. When the transmitter contact 31 again returns to the position shown, the condenser 37 is short-circuited, the grid potential is reduced and the anode current ceases to flow.

It should be mentioned that with a modified form of clutch giving sufficiently rapid starting of the disc it would be feasible to dispense with the additional transmitter contact 7 and to connect brush 14 direct to the tongue 4 of the receiving relay 3. The use of transmitter 7 controlled by magnet 5 to give a delayed action is only desirable to overcome possible difficulties due to the slow starting of the disc when the latch is released by member 11.

It will of course be understood that retransmitting relay 20 may be arranged to transmit re-generated signals over a plurality of lines if this is for any reason desirable.

By the regenerative arrangement according to the invention, therefore, signals which have been

come seriously distorted may readily be restored to their original shape and thus the possible range of telegraph transmission with simple known equipment is considerably extended at small cost.

5 What we claim as new and desire to secure by Letters Patent is:

1. In a start stop telegraph system, means for receiving signal impulses, means for retransmitting only a small unit portion of each received impulse regardless of the length of the received impulse, a retransmitting relay, and means for converting the unit portions of retransmitted impulses into impulses of standard length, and transmitting them to the retransmitting relay, and means controlled by said retransmitting relay for repeating said standard length impulses.
2. In a start-stop telegraph system, a regenerative repeater comprising a relay operated in response to a received signal comprising a series of impulses, a segmented disc, means controlled by said relay for rotating said disc one revolution for each energization of said relay, a relay for retransmitting impulses corresponding to the impulses of said received signal, and a circuit controlled by said disc for operating said retransmitting relay.
3. In a start-stop telegraph system, a regenerative repeater comprising means responsive to received signals consisting of a series of impulses for retransmitting only a small unit portion of each impulse in the received impulse, an oscillating circuit to which said impulses are retransmitted including a condenser and the primary of

a transformer, the retransmitted impulses fully charging said condenser.

4. In a start-stop telegraph system, a regenerative repeater comprising a segmented disc and brushes and means responsive to received impulses for operating said disc, a tuned oscillatory circuit, said disc operating to retransmit to said tuned circuit only a sufficient portion of the received impulses such that current in the tuned circuit is zero when the brush leaves a segment.

5. In a start-stop telegraph system, a regenerative repeater comprising means operated responsive to received impulses for transmitting a unit portion of each impulse, said means including a pair of brushes and two relatively movable segmented discs, said discs movable to alter the length of retransmitted impulses over said brushes.

6. In a telegraph system of the start-stop type, a regenerative repeater, including segmented discs operated responsive to a received signal to retransmit only a unit portion of each received impulse, a thermionic valve, a retransmitting relay in the anode circuit thereof, said discs controlling the grid potential of said valve to in turn operate said relay.

7. A system such as claimed in claim 6 having a condenser and a resistance connected to the grid circuit of the valve to maintain a potential on the grid throughout the retransmission of a signal to prevent distortion thereof.
